[57] **ABSTRACT**

A textile spindle adapted to support a bobbin for rotation while building a yarn package thereon having a replaceable driving bushing on the spindle blade for maintaining the bobbin in driving relation with the spindle.

3 Claims, 3 Drawing Figures

PATENTED JAN 1 1974

3,782,660

FIG. 1.

-FIG. 2.

A cross-sectional view of a vertical wood panel. The panel is labeled with the number 11. A central vertical cavity is labeled 25. The left side of the panel is labeled 26. The bottom edge of the panel is labeled 24. The bottom-most horizontal part of the panel is labeled 17. The right side of the panel is labeled 21. The top edge of the panel is labeled 22.

FIG. 3.

TEXTILE SPINDLE

BACKGROUND OF THE INVENTION

The invention pertains to textile spindles which are supported in an upright position on the rail or frame of spinning or twisting machines. More particularly the invention relates to an improved drive for maintaining a bobbin in driving relation with its respective spindle during rotation thereof and while building a yarn package on the bobbin.

A well known type of spindle to which the present invention is applicable is made with a tapered tip which is adapted to communicate with the drive section of a bobbin when the latter is mounted on it.

The bearing surface of the drive section of bobbins have been made with various degrees of taper, that is to say, the top fits range from a line fit up to and including a $\frac{1}{8}$ -inch conforming fit. With wooden bobbins, which are by far the most common type in use, the known types of drives are a recurring source of mill complaints and requests for an improved and trouble free type of drive are frequent.

With the line fit type of drive, bobbins are known to rise on their respective spindles when driven at high speeds and of course when such a condition occurs the driving action is immediately lost.

The various forms of drive fits wear in as the wood bearing surface of a bobbin is compressed and the bobbins under such conditions naturally assume a lower position on their spindles, thereby creating undesired lower bobbin seats. The mixing of new and old bobbins together creates a condition of non-uniform bobbin seats on the same spinning frame.

With bobbins having a very close line fit the drive section wears in much more rapidly than those of conforming fit thereby permitting said bobbins to seat lower on their respective spindles. The greater the length of the drive section of a bobbin the more difficult it is to doff due to the area of contact of the conforming fit.

In an attempt to correct the undesired conditions of difficult doffing and uneven bobbin seats textile mills frequently change from one type of fit to another. Additionally a further common and serious complaint frequently registered by mills is that of excessive wear of the spindles at the drive fit location.

Economically it is considered quite costly to purchase new or to re-work worn spindles to doff bobbins at less than the desired speed or to build less of a filling package on those bobbins which are seating lower than designed due to wear of the drive section.

The textile spindle according to the present invention has corrected the disadvantages described above by providing on the blade of a spindle provisions for the assembly of a replaceable bushing which has a configuration that permits its engagement with the inner surface of a bobbin and serves as a top drive therefor.

SUMMARY OF THE INVENTION

The textile spindle of the present invention does not include the conventional tapered tip portion which is adapted to communicate with the internal drive section of a bobbin. This portion of the spindle is removed and in the same general area there is provided a bushing locating portion intermediate the ends of and which is of lesser diameter than the so-called blade of the spindle. Integral with the bushing location portion and forming

the end of the blade there is provided a bushing retaining member of a diameter greater than said locating portion. A bushing fabricated from a material such as nylon, Delrin or the like is retained on the locating portion by the retaining member and has a configuration that permits a portion of its outer surface to engage the inner surface of a bobbin and serve as a top drive therefor.

It is a general object of the invention to provide a textile spindle having a bobbin top drive means that will perform its intended function equally well on new or used textile bobbins.

A further object is to provide a top drive for spindles which will maintain uniform seating of bobbins mounted thereon throughout the longitudinal extent of a spinning frame.

A further object is to provide a replaceable bushing for spindles which serves as a top drive for bobbins, is a relatively inexpensive replaceable item and which will substantially increase the life expectancy of a textile spindle.

These and other objects of the present invention will become more fully apparent by reference to the appended claims and as the following detailed description proceeds in reference to the figures of drawing wherein:

BRIEF DESCRIPTION OF THE DRAWING

FIG. 1 is a view in elevation and partially in section of a spindle according to the invention showing a filling bobbin assembled thereon;

FIG. 2 is a view in exploded form showing a portion of a bobbin and spindle with the latter's replaceable bushing for driving a bobbin disposed therebetween; and

FIG. 3 is a view of a portion of the assembly in FIG. 1 on an enlarged scale showing the replaceable bushing and the manner in which it engages the inner surface of a bobbin to serve as a top drive therefor.

DESCRIPTION OF THE PREFERRED EMBODIMENT

In the embodiment shown in FIG. 1 only those components of a spinning apparatus have been shown which are required for a description of the invention, including principally a textile spindle generally indicated by numeral 10 having a filling bobbin 11 assembled thereon.

This textile spindle includes such known elements as the spindle portion 12, whorl 13, acorn 14 and spindle blade 15.

As shown in FIG. 2 the spindle blade 15 adjacent its upper end is provided with a bushing locating portion 16 which is of a lesser diameter than said blade and has a cross sectional configuration which progressively changes in diameter along its longitudinal axis thus defining a taper.

A bushing 17 fabricated from nylon, Delrin or the like includes a means extending axially therethrough that defines sidewalls 18 having a configuration conforming to the frustum of a cone. This provides mating surfaces between said bushing and its locating portion 16 on the spindle blade 15.

Bushing 17 has outer surfaces which diverge away from the axis of said bushing and join at a location between the ends 19 and 20 to form a contact site 21. This contact site 21 is located further from the axis of

the bushing 17 than any other part of said bushing so as to provide for engagement with the inner surface of a bobbin 11 and serve as a top drive therefor.

The spindle blade 15 includes an upper integrally formed terminal portion which serves as a retaining member 22 for maintaining the bushing 17 on the bushing locating portion 16 of the blade 15. The outer surface of the retaining member 22 is tapered as shown at 23 to facilitate assembly of the bushing 17 onto the locating portion 16.

The resiliency of the material from which the bushing 17 is fabricated permits it to be assembled over the retaining member 22 and to be fixedly positioned on the location portion 16 by means of the lower surface of the retaining member 22 which has a diameter that approximates that of the upper end 19 of said bushing.

The preferred form of the invention shows and describes the bushing 17 as being assembled adjacent the upper end of a spindle blade 15; however, it should be understood that such a bushing could be located at any desired point along the length of the blade 15 so as to accommodate many of the various forms of spools and bobbins upon which yarn is adapted to be wound.

The bobbin 11 has a centrally disposed bore 24 (FIG. 3) which extends for a greater portion of the length of the bobbin and is adapted to receive the blade 15 of the spindle 10. The upper portion 24 as shown in FIGS. 1 and 3, communicates with a top bore 25 of lesser diameter and immediately adjacent to the point of communication of the two bores, bore 24 becomes progressively smaller and forms a so-called drive bore 26 which is adapted to be engaged by the contact site 21 of the bushing 17.

To prevent possible rotary movement of the bushing 17 on the bushing locating portion 16, the internal portion of said bushing is provided with a flat planar surface 28 and when assembled on said locating portion 16 it is caused to mate with a similar surface 27 on the latter which extends upwardly to the upper end of the spindle.

In operation a bobbin 11 is placed on the blade of the spindle as shown in FIG. 1 and the latter is caused to rotate by means well known to those conversant in the spinning art. The contact site 21 of the bushing 17 en-

gages the inner surface of the bobbin 11 in the area of the drive bore 26. By means of a slight wedging action between the contact site of the bushing and the drive bore, the bobbin is maintained in driving relation with the spindle and in addition to permitting easy doffing of the bobbin, uniform seating for either new or old bobbins is provided.

Although the present invention has been described in connection with preferred embodiments it is to be understood that modifications and variations may be resorted to without departing from the spirit and scope of the invention as those skilled in the art will readily understand. Such modifications and variations are considered to be within the purview and scope of the invention and the appended claims.

I claim:

1. A textile spindle having a spindle blade on which a bobbin is to be mounted for rotation with said spindle, said spindle blade including a bushing locating portion intermediate the ends of said spindle blade having a diameter less than the remainder of the latter with a cross sectional configuration thereof progressively changing in diameter along its longitudinal length defining a configuration conforming to the frustum of a cone, a bushing mounted on said blade at said locating portion, said bushing having outer surfaces which diverge away from the axis of said bushing and join at a location between the ends thereof to provide a contact site located further from the axis of said bushing than any other part of said bushing to provide for substantially linear contact with the inner surface of a bobbin and serve as a top drive therefor.

2. The textile spindle according to claim 1 wherein said bushing includes an opening extending axial therethrough that defines sidewalls having a configuration conforming to the frustum of a cone for providing matching surfaces between said bushing and said bushing locating portion.

3. The textile spindle according to claim 2 wherein 40 said bushing locating portion is formed adjacent the end of the spindle blade and includes an integral bushing retaining member forming the end of said spindle blade.
